HOT AIR RESPIRATOR

John E. Bjurstrom, St. Paul, Minn.

REISSUED

Application March 21, 1932, Serial No. 600,172

1 Claim. (Cl. 128—212)

My invention relates to a device most aptly designated a hot air respirator. An object of the device is to provide electrically generated heat which circulates directly to and into the nasal 5 passages or to the mouth if so desired within a shield member adapted to be pressed air tight against the face of the user.

To more readily understand my device it will first be stated that the application of heat as provided with this device comprises a healing agent and is conveyed by breathing action to infected or diseased ducts and areas inside of the head. The theory involved is that heat makes the blood and lymphatic fluids thinner and easier 15 flowing, thus penetrating the congested or infected areas more readily.

Therefore the main object is to provide a respirator to supply warm air particularly to the nose for healing infections in the head and in the 20 respiratory system. This is done by an electric heating unit as stated and provided with adjustment means for variable degrees of heat as may be needed. Said heat unit is mounted on a rubber mask which covers only the nose and 25 mouth as hereinafter fully set forth.

In the accompanying drawing,—

Fig. 1 is a top view of my device and Fig. 2 a front elevation of Fig. 1.

Fig. 3 is a side elevation of the device in operative position on the face of a patient, said face being shown in dotted lines only.

Fig. 4 is a diametrical cross sectional detail view as on line 4—4 in Fig. 3, showing a preferred form of electric heating unit.

Fig. 5 is a face view of a perforated plate P within the heating unit and through which heat circulates to the interior of the mask.

Referring to the drawing by reference numerals, my device comprises a facial mask 6, preferably of rubber and of such size and shape as to cover the nose and mouth of a patient 7 and extending from the chin to the bridge of the nose vertically and horizontally about 4 inches wide near its base, thence tapering to the upper end. 45 The rim of the mask and adjacent inner areas may be suitably padded as 8 and the entire mask being flexible, its rim parts are pressed in air tight condition against the face and may be held in place by a suitable elastic band 9 adapted 50 to be placed around the head. The mask extends forward of the nose and is tapered in that direction to a preferably circular and exteriorly flanged opening, the flange of which is designated 6F in Fig. 4, said opening being approximately 55 in a vertical plane when the mask is in position.

To the flanged forward part described is fixed an electric heating unit comprising a 2 part metal shell of which the rear part is designated 10 and resembles a shallow circular tin box of which the bottom 10B has a circular opening and 60 frictionally engages under the flange 6F of the mask. The exterior of this member is threaded to receive a correspondingly threaded front member or shell 11 of the heating unit, said latter member having a rheostat 12 suitably mounted within its front wall and having suitable wire contact with a plate 13 of insulating material, on the inner face of which is suitably fixed an electric resistance coil 14 shown as a spiral flat metal member in Fig. 4. Plate 13 is of a size to be 65 removably retained concentrically in the forward end of shell 10 and may be fixed to the inner perimetral edge of shell 11. Electric current is conducted from any available source through a plug 15 and cord 16 to the rheostat, the amount 70 of current regulated through the rheostat thence through a gap 13G to the coil 14, being regulated by a rotary button 17.

P is perforated plate intermediate coil 14 and base 10B and through the perforations of which 80 heated air is drawn to the interior of the mask as indicated by arrows 18 in Fig. 4. It is obvious that the rheostat shown is merely illustrative, it being understood that merely a variable resistance coil with suitable manipulating means therefor 85 need be provided. In my device the preferred heat generating means embodies the coil 14 of any suitable material readily generating heat within the chamber formed between plates P and 13.

19 designates a number of perforations in shell member 11 for intake of air.

The use of my respirator and its construction have now been fully disclosed. The patient does not require certain room temperatures, the heated air available within the mask being determined as required. Obviously means must be provided for exhalation and for this purpose a valve housing 20 (Fig. 3) is mounted preferably on the side of the mask and providing for air to escape only 95 during exhaling, the said valve being otherwise normally closed.

It will be also readily understood that the accompanying drawing illustrates only a preferred embodiment of my invention, various modifications being optional without departing from the scope and spirit of the invention. For example, other equally efficient construction may be used instead of the take-apart construction involving the threaded shell members 10—11.

I claim:

In a respirator of the class described and including a flexible mask adapted to bear against the face and inclose the respiratory organs; said mask provided with an opening directly forward of said organs, an air heating chamber secured to said opening part of the mask, electric heating means mounted within said chamber, said chamber provided in its forward part with air intake apertures, a perforated plate adjacent the mask opening and within the inner part of said chamber, said heating means comprising a resistance coil in an upright plane and in the path of air

currents inhaled into the mask, said heating chamber comprising two separable cylindrical housing members, an upright non-conductive perforate plate retained concentrically in the forward part of the chamber and said resistance coil secured to the inner face of said plate, a rheostat in the chamber forward of said resistance coil and electric conductors connecting the rheostat and the coil, connecting means for supplying electric current to said coil through said rheostat, and a rheostat control button accessible exteriorly of the housing for the purpose set forth.

JOHN E. BJURSTROM.
